(57) **CLAIM**

The ornamental design for hooking-type electric meter, as shown and described.

DESCRIPTION

FIG. 1 is a perspective view of hooking-type electric meter showing a status of the new design in use;

FIG. 2 is a front view of the new design;

FIG. 3 is a rear view of the new design;

FIG. 4 is a left view of the new design;

FIG. 5 is a right view of the new design;

FIG. 6 is a top view of the new design; and,

FIG. 7 is a bottom view of the new design.
